C. SPIRO.

LINE SPACE MECHANISM.
APPLICATION FILED FEB. 3, 1919.

1,319,808.

Patented Oct. 28, 1919.

Inventor,
Charles Spino
by Alfred T. Sage,
Attorney.

UNITED STATES PATENT OFFICE.

CHARLES SPIRO, OF NEW YORK, N. Y., ASSIGNOR TO GOURLAND TYPEWRITER CORPORATION, OF NEW YORK, N. Y., A CORPORATION OF NEW YORK.

LINE-SPACE MECHANISM.

1,319,808.

Specification of Letters Patent. Patented Oct. 28, 1919.

Application filed February 3, 1919. Serial No. 274,683.

To all whom it may concern:

Be it known that I, CHARLES SPIRO, citizen of the United States, residing at New York, in the county of New York and State 5 of New York, have invented certain new and useful Improvements in Line-Space Mechanism, of which the following is a specification.

This invention relates to a line space 10 mechanism and particularly to a construction adapted for application to the platen of a typewriting machine.

The invention has for an object to provide a novel and improved construction embodying a rock shaft provided with a lateral projection disposed to actuate a pivoted spacing lever carrying at its free end a feed pawl, the several parts being arranged to permit the introduction and removal of a 20 platen having a ratchet disposed in operative relation to the spacing lever and pawl.

A further object of the invention is to provide an improved construction and arrangement of feed lever and pawl adapted to be 25 rocked away from a co-operative ratchet wheel when the parts are at rest and to be moved toward said ratchet during the movement of the lever for a spacing operation.

Other and further objects and advantages 30 of the invention will be hereinafter set forth and the novel features thereof set forth by the appended claims.

In the drawing—

Figure 1 is a top plan showing the invention applied in use;

Fig. 2 is a section on line 2—2 of Fig. 1;

Fig. 3 is an end elevation at the left of Fig. 1;

Fig. 4 is a detail rear elevation at the left 40 end;

Fig. 5 is a section on line 5—5 of Fig. 1; and

Fig. 6 is a detail of spacing feed pawl.

Like numerals indicate like parts in the 45 several figures of the drawing.

The numeral 10 designates the platen frame which may be of any desired construction or configuration. As herein shown it is composed of the opposite end risers 11 50 connected at their lower front portion by a cross bar 12 and at their upper rear portion by a bar 13. These risers are constructed to receive a removably mounted platen 14, and for that purpose are provided with the bearings 15 having inlet slots 16 of less diameter

communicating therewith. The ends 17 of the platen shaft are of a diameter to properly fit these bearings and are each provided with a reduced portion 18 adapted to pass through the slots 16 when the platen is introduced into or removed from the frame. After such introduction the platen and shaft are moved axially to bring the bearing portions of the shaft into contact with the bearings in the risers. This form of removable 65 platen is not claimed herein, as it is the subject of a separate application filed January 13, 1919, Serial No. 270,912.

For the purpose of effecting the line spacing one of the risers 11 is provided with 70 bearing lugs 20 in which a rock shaft 21 is mounted and provided with an operating hand piece 22 adjustably mounted thereon and secured in any desired manner, for instance by a set screw 23. This shaft and 75 handle are normally retained in non-operative position, for instance with the hand piece inclined toward the left, by a spring 24 encircling the shaft and secured thereto at one end 25. The opposite end of the spring 80 is secured at 26 to one of the lugs 20. The shaft carries at its rear a laterally extending pin or projection 27 which passes through the slotted end 28 of the spacing lever 29 pivoted at 30 upon the inner face of the 85 riser.

This space lever is provided at its front end with a feed pawl 31 pivoted thereon at 32 and having its tooth 33 normally forced inward by a spring 34 secured at the pivot 90 32 and bearing against said tooth. For the purpose of retracting this pawl and tooth when withdrawn from the ratchet 35 secured to the platen or its shaft, the pawl is formed with a tail portion 36 arranged to 95 engage the front cross bar 12 of the platen carriage when the parts are at rest, as shown by full lines in Fig. 2. As the lever is under the tension of the rock shaft spring this results in rocking back the feed pawl so that 100 the platen and its ratchet wheel are free to be removed and replaced without affecting the relative feeding position of the pawl to said wheel. When the pawl is removed from the cross bar by operation of the rock 105 shaft it is thrown toward the ratchet and into proper position to engage the teeth thereof to effect the line spacing action.

In order to determine the extent of travel 110 of the space lever for different degrees of

line spacing a variable space lever 37 is pivotally mounted upon the riser at 38 and provided with a friction washer 39 to retain the lever in adjusted position. The lower end 5 of the lever 37 is provided with a hook 40 disposed to pass beneath the projection 27 from the rock shaft and its movement into this position is limited by a stop 41, as shown in Fig. 3. When thus positioned the 10 space lever is restricted in its travel for the shortest spacing, but when shifted to the dotted line position in Fig. 3 the hook is removed from the path of the pin 27 and the fullest extent of spacing permitted.

15 In order to hold the platen against accidental movement when the spacing pawl is removed therefrom any desired form of detent may be used, such for instance as the 20 roller 42 carried by a spring arm 43 mounted on the rear cross bar 13 and bearing against a detent ratchet 44 at the right end of the platen. The pressure of this detent may be relieved by a release lever 45 pivoted at 46 upon the riser and having at its inner 25 end a lateral finger 47 disposed to engage and move backward the extended pivot 48 of the detent roller, as shown in Figs. 1 and 5.

In the operation of the invention when 30 the hand piece is moved toward the right the rock shaft is turned to actuate the spacing lever carrying the feed pawl which is normally held away from the platen ratchet wheel by its contact with the front cross bar. This movement releases the pawl which is rocked toward the ratchet by its spring so as to properly mesh therewith and feed the same for the distance determined by the position of the variable space lever 35 40 which is frictionally held in either of its shifted positions. When the parts are at rest the spacing lever pawl lies below and away from the ratchet wheel so that the platen may be readily removed or replaced 45 in its frame without interference with the spacing mechanism which in its preliminary movement is released and thrown into meshing relation with the ratchet for the feeding action. It will thus be seen that this construction is particularly designed and adapted for use in connection with a platen 50 which can be quickly and easily removed from its frame, for any purpose desired, and replaced by a platen of different type or 55 character.

The invention presents a simple, efficient and economically manufactured construction of line spacing mechanism, and while the specific structure of the several parts 60 thereof has been described and shown, the invention is not limited thereto as set forth in the following claims.

What I claim is—

1. A line spacing mechanism comprising 65 a platen frame, a platen mounted therein

and provided with a feeding ratchet, a rock shaft pivoted upon said frame and having a lateral projection, a spacing lever disposed in a horizontal plane parallel to said shaft and pivoted upon the frame beneath 70 said platen and engaging said projection, and a feed pawl carried by the free forward end of said lever to engage said ratchet.

2. A line spacing mechanism comprising a platen frame, a platen mounted therein 75 and provided with a feeding ratchet, a rock shaft pivoted upon said frame and having a lateral projection, a horizontally disposed spacing lever pivoted upon the frame beneath the axis of said platen and engaging 80 said projection, a feed pawl carried by the free end of said lever to engage said ratchet, and means beneath said lever to rock said pawl upon its pivot to retract the same when the lever is at rest.

3. A line spacing mechanism comprising a platen frame, a platen mounted therein and provided with a feeding ratchet, a rock shaft pivoted upon the frame and having a lateral projection, a horizontally disposed 90 spacing lever pivoted upon the frame beneath the axis of said platen and engaging said projection, a feed pawl carried by the free end of said lever to engage said ratchet, means beneath said lever to rock said pawl 95 upon its pivot to retract the same when the lever is at rest, and a variable space lever pivoted above the projection and having means at its lower end to travel beneath said projection to determine the extent of 100 its travel.

4. A line spacing mechanism comprising a platen frame, a platen mounted therein and provided with a feeding ratchet, a spacing lever pivoted upon the frame in a 105 horizontal plane beneath said ratchet, a feed pawl pivoted upon the free end of said lever, tension means to throw said pawl toward said ratchet, and means disposed beneath the free end of said lever to engage 110 and retract said pawl when the lever is at rest.

5. A line spacing mechanism comprising a platen frame, a platen mounted therein and provided with a feeding ratchet, a 115 spacing lever pivoted upon the frame in a horizontal plane beneath said ratchet, means for actuating the rear end of said lever, a feed pawl pivoted upon the forward end of said lever beneath said ratchet, a tail upon 120 said pawl disposed beneath its pivot, means upon the lever for throwing said pawl toward said ratchet, and fixed means disposed beneath the forward end of the lever to engage said tail and retract the pawl 125 upon the vertical depression of said lever.

6. A line spacing mechanism comprising a platen frame provided with open bearing sockets, a platen having its shaft removably mounted therein and provided with a feed- 130

- ing ratchet, a spacing lever pivoted upon the frame in a horizontal plane beneath said shaft, a rock shaft mounted upon the frame and having a lateral pin engaging the rear 5 end of said lever, means upon the frame adapted to be disposed beneath said pin and limit the travel thereof, a feed pawl carried by the forward end of said lever, means for throwing said pawl toward said ratchet, 10 and means for retracting said pawl when the same is moved into a plane below said ratchet.
7. A line spacing mechanism comprising a platen frame having risers at opposite 15 ends, a platen having its shaft removably mounted therein and provided with a feeding ratchet, a rock shaft pivoted upon the outer face of one riser and having a lateral pin extended from the inner end thereof, a 20 spacing lever pivoted upon the inner face of said riser parallel with said rock shaft and having a slotted inner end to receive said pin, and a feed pawl carried by the forward end of said lever and disposed to travel toward and from said ratchet.
8. A line spacing mechanism comprising a platen frame having risers at opposite ends, a platen having its shaft mounted 25 therein and provided with a feeding ratchet, a rock shaft pivoted upon the face of one riser and having a lateral pin extended therefrom, a variable space lever pivoted upon said riser and having a member disposed to enter the path of travel of 30 said pin, a spacing lever pivoted upon the
- riser parallel with said rock shaft and connected at its inner end with the free end of said pin, and feed pawl carried by the forward end of said lever and disposed to travel toward and from said ratchet. 40
9. A line spacing mechanism comprising a platen frame having risers at opposite ends, a platen having its shaft mounted therein and provided with a feeding ratchet, a rock shaft pivoted upon the face 45 of one riser and having a lateral pin extended therefrom, a variable space lever pivoted upon the riser and having a hooked lower end disposed to enter the path of travel of said pin, means to retain said lever 50 in shifted positions, a spacing lever pivoted upon the riser and connected with the free end of said pin, and a feed pawl carried by said lever and disposed to travel toward and from said ratchet. 55
10. A line spacing mechanism comprising a platen frame, a platen having its shaft mounted therein and provided with a feeding ratchet, a spacing lever pivoted upon the frame, means for actuating the inner 60 end of said lever, a feed pawl pivoted upon the outer end of said lever, a spring bearing upon the tooth of said pawl, and an angularly disposed tail upon said pawl arranged to engage a portion of said frame to 65 retract the pawl as the lever is moved away from said ratchet.

In testimony whereof I affix my signature.

CHARLES SPIRO.
